US0D1048014S

(12) **United States Design Patent** (10) Patent No.: **US D1,048,014 S**
(45) Date of Patent: ** Oct. 22, 2024

(54) **BARCODE READER**

(71) Applicant: **Yihua Yu**, Shenzhen (CN)

(72) Inventor: **Yihua Yu**, Shenzhen (CN)

(73) Assignee: **Shenzhen Effon LTD**, Shenzhen (CN)

(**) Term: **15 Years**

(21) Appl. No.: **29/862,914**

(22) Filed: **Dec. 14, 2022**

(51) LOC (14) Cl. **14-02**

(52) U.S. Cl.

USPC **D14/427**; D14/420
